Inventor:

Albert E. Guy.

UNITED STATES PATENT OFFICE.

ALBERT E. GUY, OF WASHINGTON, DISTRICT OF COLUMBIA.

APPLYING PRESSURE TO THE INTERIOR OF CLOSED VESSELS.

1,369,890.

Specification of Letters Patent.

Patented Mar. 1, 1921.

Application filed November 20, 1918. Serial No. 263,398.

(FILED UNDER THE ACT OF MARCH 3, 1883, 22 STAT. L., 625.)

To all whom it may concern:

Be it known that I, ALBERT E. GUY, major, Ordnance Department, U. S. A., a citizen of the United States, stationed at Washington, 5 District of Columbia, have invented an Improvement in Applying Pressure to the Interior of Closed Vessels, of which the following is a specification.

The invention described herein may be 10 used by the Government, or any of its officers or employees in prosecution of work for the Government, or by any other person in the United States without payment of any royalty thereon.

15 This invention relates to a method of applying pressure to the interior of closed vessels, and involves an application of the laws of expansion of fluids and solids under change in temperature by means of suitable apparatus.

20 The invention is useful in treating the walls to increase their resistance to internal pressure, and is intended particularly for gun tubes, which must withstand very high internal pressure each time a shot is fired; 25 but it is not restricted to gun tubes. It is also adapted for fitting linings in cylinders, tubes, and the like, and especially for relining gun tubes. It is very well adapted for 30 use in connection with the process of treating tubes by pressure described in my application Serial No. 258,652, filed October 17, 1918.

The objects of the invention are rapidity 35 and ease of operation, low cost and adaptability to different conditions of manufacture and use. The invention consists in the method and in the apparatus hereinafter described and claimed.

40 The preferred means and mode of applying the invention to a gun tube is as follows, reference being made to the accompanying drawings which show suitable apparatus for carrying out the invention. The same characters are used to designate the same or similar parts in the several views.

Figure 1 of the drawings is a side view, partly in section, of a gun tube, wherein a liner is to be secured by an application of 50 this method;

Fig. 2 is a similar view showing the method as applied to a one piece gun tube.

The gun forging 10 is rough turned or forged to approximately its final dimen-

sions on the exterior, the interior being left 55 slightly smaller than the finished size.

A rod or core 12 is arranged to extend entirely through the gun and beyond its ends, each end of the rod is provided with a washer seat 13 adapted to receive a washer 60 14 which fits across and closes the end of the tube. The rod may be screw threaded at one end and extend beyond the washer to receive a nut 15, which is screwed tight to secure the washers firmly in place. 65

In order to seal the ends of the gun tube, washers are inserted as shown at 16, and annular rings 17 secured by set screws 18 are arranged in contact with the washers to form a perfect joint between the parts. 70

Any liquid preferred having a higher coefficient of expansion than the containing parts of the gun and apparatus, is permitted to circulate through the space 19 between the core 12 and the inner wall of the 75 liner. Thermostatic circulation is maintained through metal tubing 20 communicating with a bore 20^a in the ends of the rod or core 12 and opening into the space 19. The tubing 20 is of relatively small 80 bore to withstand the pressure, and is coiled intermediate its ends, the coil portion 21 being mounted in a heater 22.

When heat is applied to the coil 21 the temperature of the liquid is raised, and as 85 the expansion of the liquid is greater than that of the tubing, pressure is applied to the inner face of the tube, as the temperature of the liquid in the tube is maintained in circulation by thermostatic pressure 90 through the pipe 20, and the coil 21 in the direction indicated by the arrows in Fig. 1.

A gage 23 may be inserted in the circulating system to indicate the pressure, and a thermometer 24 to indicate the temperature, 95 of the circulating medium to facilitate accurate application of the method to the desired limit.

The pressure produced within the gun tube by the means described may be designed sufficient to stretch the inner wall of the gun beyond the elastic limit of the steel, and a permanent deformation or "set" of the inner layers of the steel is the result. The operation is stopped before the outer 100 layers are stretched to their elastic limit. When the pressure is relieved, the outer layers of the steel tend to return to their

original size, thereby compressing the inner layers, which have been stretched too far to return to their original size and which remain slightly stretched and hence become under compression from the outer layers. The condition of the metal in the inner and outer regions of the gun tube after treatment by this method is similar to that of a complete gun formed by shrinking outer bands on the inner tube to compress the metal.

Following the pressure treatment and the removal of the parts of the apparatus above referred to, the gun is ready for rifling, fitting the breech and finishing in the usual manner.

What I claim is:

1. The method of applying pressure generated by external heating means to the inner surface of tubes by fluid in a closed system.

2. The method of applying pressure to the bore of a tube, consisting of including said tube in a sealed circulating system containing a substance expansible under temperature and applying heat thereto remote from the tube. 25

3. The method of applying pressure generated by external heating means, to the inner surface of a tube, consisting of causing a liquid to expand by heat and to circulate through the tube and a sealed circulating system. 30

4. The method of securing a liner in a tube by expansion consisting of including said liner in a sealed system and expanding by heat the contents of the system. 35

5. The method of treating the inner surface of a gun tube or its liner, consisting of including same in a sealed circulating system filled with liquid and heating the liquid. 40

ALBERT E. GUY.
